CLAIM

The ornamental design for a “chair”, as shown and described.

DESCRIPTION

FIG. 1 is perspective view of the chair according to the present invention;

FIG. 2 is front elevational view of the chair shown in FIG. 1;

FIG. 3 is back elevational view of the chair shown in FIG. 1;

FIG. 4 is left side elevational view of the chair shown in FIG. 1;

FIG. 5 is right side elevational view of the chair shown in FIG. 1;

FIG. 6 is top plan view of the chair shown in FIG. 1; and,

FIG. 7 is bottom plan view of the chair shown in FIG. 1.

(Continued)

The broken lines shown in the drawings are included for the purpose of illustrating portions of the article and form no part of the claimed design.

1 Claim, 7 Drawing Sheets
